FIG. 1

FIG. 2

FIG. 3.

FIG. 4.

FIG. 5.

INVENTOR

Lawrence W. Luellen

UNITED STATES PATENT OFFICE.

LAWRENCE W. LUELLEN, OF MOUNTAIN LAKES, NEW JERSEY, ASSIGNOR TO INDIVIDUAL DRINKING CUP COMPANY, INC., OF EASTON, PENNSYLVANIA, A CORPORATION OF PENNSYLVANIA.

RECEPTACLE.

Application filed May 6, 1922. Serial No. 558,891.

The United States Letters Patent No. 1,308,793, heretofore granted to me on July 8th, 1919, disclosed a drinking cup formed from a single piece of paper having its side walls constructed by pleating the paper upon itself, the side folds being held together so as to retain the cup shape by coating and impregnating the paper with paraffin, which cements the folds in proper position.

The paper cup of the character just described while having been manufactured and sold in enormous quantities, has been restricted in use primarily to cold drinks and liquids, and has been unsuited for hot drinks for several well-known reasons. The paraffin which is relied upon to retain the pleats or folds in proper position, is susceptible to melting under the heat of the hot liquid when poured into the cup, and which on account of its lighter specific gravity will float on top of the liquid and spoil the drink. Furthermore, the melting of the paraffin permits the cup folds to open up, thus breaking down the walls under the weight of the liquid and destroying the usefulness of the cup.

My present invention eliminates the objectionable characteristics alluded to, and has for its object the construction of a one-piece paper cup, that will be serviceable as a holder for heated or hot drinks or liquids, and which will, when filled therewith, retain its rigidity and shape for the time necessary for the consumption or use of the contained liquid.

To accomplish this, I provide means whereby the pleats or folds of the cup, of which the walls are comprised, are held together and retained in their engaging overlapping position, so as to counteract the natural tendency of the pleats to unfold under the influence of heat and moisture. The means employed consists in providing a reinforced rim portion formed by imparting to the rim a particular form of re-enforcement by a rolled outwardly extending flange, and re-enforced by a reverse and concave configuration of the paper in the rim of the cup.

This composite rim is then put under pressure of forming dies which crinkles the under-surface of the rim, crushing the laminae of the paper into close and intimate

association. This results in a stiffening of the rim, thus providing a substantial re-enforcement at the top of cup, which prevents the flutes or pleats from loosening up or becoming disengaged, which would otherwise cause the cup to break down when in use.

This invention enables the cups to be manufactured more uniformly, and owing to the restriction of expansion due to this particular re-enforcement, the cups will more perfectly maintain their dimensions and conformation, and when in use in cup dispensing devices, they will more freely separate one from the other, as is desirable.

While the principles of my invention may be embodied in divers forms of receptacles, I have chosen to illustrate a single embodiment which I consider as best suited for the service of hot drinks.

Referring to the accompanying drawings,—

Figure 1 is a view in side elevation of a one-piece paper drinking cup, embodying the principles of my invention.

Figure 2 is a view in vertical section thereof, and

Figure 3 is a bottom plan view thereof.

Figure 4 is a fragmentary section on an enlarged scale of a portion of the cup, and in section, showing a portion of the side walls and rim of the cup.

Fig. 5 is a detail section, on an enlarged scale, of a portion of the rim taken on the line 5—5 of Figure 3.

Similar numerals of reference indicate like parts throughout the respective views.

The cup is formed of a single sheet of paper or other fibrous material, the blank of which it is formed being of circular shape, the central zone 1 thereof being utilized to form the bottom of the cup, the side wall 95 and rim of the cup are formed by so-called pleating as at 2 and 2', in a tapering fashion so that the upper opened end of the cup is larger in diameter than the bottom. Of course, it will be understood that the size and form of taper will vary under certain circumstances, according to the general contour of the receptacle desired.

By pleating the cup in the fashion described a number of superimposed layers are provided, which constitute as it were re-enforcing ribs which to a considerable degree strengthen the cup, these re-enforcing ribs

at the outer terminating portion of the cup, admirably serve my purpose in providing a very substantial flanged or rim portion 2', which when given the conformation intended by my invention adds very materially to the normal strength of the article, holding the same firmly in shape, and preventing under ordinary use the distortion or expansion of the side walls. The flange or re-enforced 10 lip portion of the cup 2', is formed by flaring outwardly the circumferential edge and reversing the same upon itself as shown more particularly in enlarged detail in Figure 4. This is accomplished by using suitable molds or dies which fold the material 15 over in this fashion.

The paper rim is circumferentially crinkled, as indicated in Figures 3 and 5, sufficient pressure being utilized to bring the 20 laminations into practical homogeneous association. The crinkling serves to increase the stiffening of the rim to a very material extent, and it is by reason of the re-enforced 25 stiffness of the rim that governs the strength of the cup, and its ability to withstand lateral expansion. Also, it is the stiffness of the rim which holds the pleats or flutes of the 30 cup together, because no paraffin is used for that purpose as described in my previous Letters Patent above referred to.

What I claim is:

1. A one-piece pleated paper cup provided with an integral outstanding rim formed by bending an upper marginal portion of

the cup outwardly and then backwardly upon itself, said rim being crinkled under pressure at intervals thereabout for retaining the pleats in close overlapping relation. 35

2. A one-piece pleated paper cup provided with an integral outstanding rim formed by bending an upper marginal portion of the cup outwardly and then back upon the under side thereof, the outer edge of the reversely bent portion of the rim abutting against the adjacent outer face of the cup. 40 45

3. A one-piece pleated paper cup provided with an integral outstanding rim, the laminations formed by the pleats of the cup at the rim being tightly compressed to form 50 indentations at spaced points about the rim for retaining the pleats in close overlapping relation.

4. A one-piece pleated paper cup provided with an integral outwardly extending rim formed by bending an upper marginal portion of the cup outwardly and then back upon itself, said rim being formed concave and crinkled on its under side under pressure at 55 intervals thereabout for retaining the pleats in close overlapping relation. 60

5. A one-piece pleated paper cup provided with an integral outstanding concave rim formed by bending an upper marginal portion of the cup outwardly in a curve and then back upon the under side thereof. 65

In testimony whereof I have affixed my signature to this specification.

LAWRENCE W. LUELLEN.
